UNITED STATES PATENT OFFICE.

CHARLES D. MOSHER, OF NEW YORK, N. Y.

EXPANSIBLE PLUG.

SPECIFICATION forming part of Letters Patent No. 787,460, dated April 18, 1905.

Application filed October 2, 1903. Serial No. 175,476.

To all whom it may concern:

Be it known that I, CHARLES D. MOSHER, a citizen of the United States, residing at New York, in the county of New York and State of New York, have invented certain new and useful Improvements in Expansible Plugs, of which the following is a specification.

My invention relates to plugs for boilers, condensers, and like structures where the metal forming the shell is too thin to permit them to be threaded and in cases where it is desirable and necessary to readily remove the plug.

The invention has special reference to plugs which are expanded into place; and the object is to construct a plug which will more readily yield to the expanding-tool and when expanded will be firmly seated on the rim of the hole, as will now be set forth more fully.

In the drawings, Figure 1 is a cross-section 20 of the shell of a boiler and a plug resting therein preparatory to expanding same. Fig. 2 is a cross-section of the same, showing the plug expanded in position. Fig. 3 is a cross-section of a plug, showing an internal annular 25 corrugation; and Fig. 4 is a cross-section of a plug which is provided with several annular corrugations.

In preparing the shell 8 I form the hole 6 in the usual manner, with the corners chamfered away, as shown at 7. The plug 5 is stamped out of sheet metal, cup-shaped; as shown, with an exterior flange 9, the side of the cup being tapered, as shown at 10, and the base of the cup is rounded or crowned, as at 11.

As illustrated in Fig. 1, the side wall near the base has an annular bulging portion 12, which in practice extends out so that the diameter of this bulging portion is the exact diameter of the hole 6 in the shell 8, and it will be observed that when the plug is in position the exterior diameter of the plug next to the flange 9 is also the diameter of the hole 6. Constructed in this manner there is an internal annular ridge or raised portion 13, which is substantially on the same plane as the inner edge of the shell 8, so that when the expanding-tool is applied to this ridge and forced outwardly the shell of the plug will more readily yield than otherwise and cause 45 the exterior body of the plug to seat itself against the inner rim of the hole, as shown in Fig. 2.

I may modify somewhat the structural formation, particularly so far as concerns the relative location of the interior ridge; but the 55 essential features of the invention relate to the slightly-tapering cup-shaped plug and to the exterior annular bulging portion of the base, together with the internal ridge to serve as a bearing-point for the expander when in use. 60

It is not material whether the annular corrugations project externally, as in Fig. 1, or internally, as in Fig. 3. The latter form has some advantages in point of construction, particularly where the plugs are made of thick 65 material. It will be noted that the side wall 14 need not be tapered, as in Fig. 1; but in such case I prefer to make a pronounced internal annular corrugation 15, against which the expanding-tool acts during the process of 70 expanding.

In Fig. 4 I provide a single internal corrugation 16, and two external annular corrugations 17 18, as thereby the body of the cup or plug will the more readily yield to the action 75 of the expander, as well as to permit me to make the plug of heavy metal.

What I claim as new is—

1. A cup-shaped expansible plug provided with an annular interior bulging portion near 80 its base, in combination with a shell having a hole therein and adapted to receive said plug.

2. A cup-shaped expansible plug having tapering sides and provided with an interior annular bulging portion near its base, in combination with a shell having a hole therein 85 and adapted to receive said plug.

3. A hollow or cup-shaped expansible plug having corrugations near its inner end.

4. A hollow or cup-shaped expansible plug 90 having corrugations near its inner end, in combination with a shell having a hole in which said plug is expanded.

5. A hollow or cup-shaped plug with tapering sides and corrugations at its inner end, in 95 combination with a shell having a hole therein, said corrugated portion being expansible against the inner surface of the shell.

In testimony whereof I affix my signature in presence of two witnesses.

CHARLES D. MOSHER.
